(57) **CLAIM**

The ornamental design for an electronic housing, as shown and described.

DESCRIPTION

FIG. 1 is a front perspective view of an electronic housing showing our new design;

FIG. 2 is a top view thereof;

FIG. 3 is a front view thereof;

FIG. 4 is a rear view thereof;

FIG. 5 is a right side view thereof; and,

FIG. 6 is a left side view thereof.

The broken line showing of various features of the electronic housing is for environmental purposes only and forms no part of the claimed design. The contrast in shading represents a contrast in appearance only and does not represent any particular color, texture or finish.
